Meyer Cohen, Flushing, N. Y., assignor to Agency
Paper Company, New York, N. Y.

Application January 11, 1946, Serial No. 125,440

Term of patent 14 years

(Cl. D59—14)

To all whom it may concern:

Be it known that I, Meyer Cohen, a citizen of the United States, residing at Flushing, in the county of Queens and State of New York, have invented a new, original, and ornamental Design for Writing Paper or Similar Article of Stationery, of which the following is a specification, reference being had to the accompanying drawing, forming part thereof.

The figure is a face view of a sheet of writing paper or similar article of stationery, showing my new design.

I claim:

The ornamental design for writing paper or similar article of stationery, as shown.

MEYER COHEN.
